UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 25,226, dated March 3, 1896.

Application filed December 16, 1895. Serial No. 572,371. Term of patent 3½ years.

To all whom it may concern:

Be it known that I, FREDRIC M. PARKER, a citizen of the United States, residing at Worcester, in the county of Worcester and 5 Commonwealth of Massachusetts, have invented and produced a new and original Design for Carpets, of which the following is a specification.

My invention relates to a design to be 10 worked into or upon carpeting or other similar fabric; and I do hereby declare that the drawing accompanying this specification gives and conveys to any one skilled in the art of carpet-weaving a clear understanding of the same 15 that is sufficient to enable such person to use my invention.

The said drawing is a face view of a carpet embodying my design.

The drawing illustrates a body and a border. 20 The body A consists of a substantially uniform groundwork, upon which appear similar figures arranged diagonally as to each other. Each figure consists of a vertical stem spreading into a leafy ornamental top and having 25 a lozenge-shaped base. Upon each side is placed flowing leafwork, curving into scrolls at each end. These are all connected by a straight horizontal bar, so as to form one figure having the general characteristics of a 30 fleur-de-lis. The bottom scrolls of each figure are connected with the top scrolls of each figure diagonally below it by hanging festoons of flowers and leaves.

The border B consists of a groundwork of substantially the same character as the body 35 A. On this appears the same figure as in the body of the carpet. Beneath this figure is a festoon or hanging wreath of flowers and leaves, appearing to be attached to the outer margin by a bow of ribbon with loose or flying ends. The inner margin of the border 40 is defined by a series of small figures or fleur-de-lis, connected with each other by three links. The outer margin consists of a series 45 of ornamental leafy figures resembling the ornamental top of the central stem of the figure in the body A. Between these is placed a different figure of the same style. These figures appear to rest upon a narrow ornamental band.

The colors employed for the different portions of this design may be varied to suit the taste or convenience of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the 60 body A and the border B, substantially as shown.

FREDRIC M. PARKER.
